United States Patent Office

Des. 209,080

Patented Oct. 31, 1967

209,080

DESK LAMP

Hiroshi Daito, Kyoto, Japan, assignor to Blackwell Electronics Ind., Co., Shimogyo-ku, Kyoto, Japan, a corporation of Japan

Filed Mar. 16, 1967, Ser. No. 6,251
Term of patent 14 years

Claims priority, application Japan Aug. 27, 1966

(Cl. D48—20)

FIGURE 1 is a perspective view of a desk lamp showing my new design;

FIGURE 2 is a front elevational view;

FIGURE 3 is a rear elevational view;

FIGURE 4 is an elevational view from one side;

FIGURE 5 is an elevational view from the opposite side;

FIGURE 6 is a top plan view; and

FIGURE 7 is a bottom elevational view.

I claim:

The ornamental design for a desk lamp, as shown.
